UNITED STATES PATENT OFFICE.

SAMUEL R. JOFFE, NATHAN JOFFE, AND LOUIS F. MAHLE, OF ROCHESTER, NEW YORK;
SAID SAMUEL R. JOFFE ASSIGNOR TO SAID NATHAN JOFFE.

NON-REFILLABLE BOTTLE.

1,128,452.

Specification of Letters Patent. Patented Feb. 16, 1915.

Application filed October 6, 1913. Serial No. 793,505.

To all whom it may concern:

Be it known that we, SAMUEL R. JOFFE, NATHAN JOFFE, and LOUIS F. MAHLE, of the city of Rochester, in the county of Monroe and State of New York, have invented 5 certain new and useful Improvements in Non-Refillable Bottles; and we do hereby declare the following to be a full, clear, and exact description of the same, reference being had to the accompanying drawings, 10 forming a part of this specification, and to the reference-numerals marked thereon.

Our present invention relates to non-refillable bottles and it has for its object to 15 provide a simple, cheap and practical device of this character, which will be efficient in use, but which may be manufactured by ordinary processes familiar to the art, whereby the usual prohibitive expense incident to the commercial production of 20 many devices of this kind will be obviated.

A further object of the invention is to provide a check valve mechanism of such 25 sensitiveness that the valve or stopper will assume its closed position even when the bottle neck is in a substantially horizontal position whereby a pronounced tilting movement is required to unseat it with the bottle held at such an angle as to make refilling 30 in that position practically impossible.

Our invention is also directed toward providing means for sealing the bottle and the outer stopper or cork thereof by a simple expedient combined with the structure producing the non-refilling functions. 35

To these and other ends the invention consists in certain improvements and combinations of parts, all as will be hereinafter more fully described, the novel features being pointed out in the claims at the end of the specification. 40

In the drawings: Figure 1 is a vertical central section through a bottle neck and stopper mechanism constructed in accordance with and illustrating one embodiment 45 of our invention, the parts being shown in their normal positions, which are the positions they assume when the bottle is upright; Fig. 2 is a similar view showing the relative positions of the parts when the bottle is tilted for the purpose of pouring out the contents; Fig. 3 is a similar view showing the relative positions of the parts when the bottle is held with the neck substantially horizontal; Fig. 4 is a bottom 50

plan view of the upper portion or cap piece of the neck, and Fig. 5 is a top plan view of the device.

Similar reference numerals throughout the several figures indicate the same parts. 60

In the practice of our invention the lower or body portion 1 of the neck may be formed in substantially the same manner as the neck proper of an ordinary bottle with a slightly rounded or flaring mouth which, 65 in the present instance, constitutes a seat 2 for the stopper valve hereinafter described. Resting on the neck is a cup-shaped cap piece or upper neck portion 3 having a restricted mouth or discharge opening 4 closed 70 by an outer stopper 5 provided with a head 6. The lateral and top walls of the portion 3 are preferably provided with ribs 7 and 8 that leave open channels between them for the flow of liquid even though other bodies 75 may be resting against them, as will later appear.

A suitable gasket 9 is preferably interposed between the two portions of the neck to form a liquid-tight joint and they are 80 rigidly held together by spinning upon or otherwise applying to the exterior an encircling band or collar 10 which spans the joint 9, is flanged over upon the top shoulder of the cap piece 3 and which interlocks 85 at the bottom with a suitable ridge or other irregularity 11 formed on the exterior of the lower neck portion 1. The parts inclosing the stopper valve mechanism hereinafter described are thus held securely together 90 and at the same time we utilize the band 10 for sealing the bottle as a whole by passing a seal strip 12 over the head 6 of the outer stopper 5 and securing the ends beneath the band in the manner clearly shown in 95 Fig. 1. To open the bottle, therefore, in the first instance it is necessary to break this strip 12 which can readily be done along the line indicated at 13 in Figs. 2 and 3, which show the bottle uncorked. 100

The stopper valve 14 may be substantially semi-spherical in form, as shown, and comprises an upper hollow enlarged portion 15 that normally occupies and seals the seat 2 and a lower approximately solid reduced portion 16, smaller in diameter than the seat, and preferably having an excess of material 17 that provides a weight at the lower end of the stopper. With the bottle upright, this weight, of course, tends to hold 110

the enlarged portion in firm engagement with the seat 2. While in this position it might be possible to raise the stopper valve by gripping its top edge or its hollow interior with a suitable tool or instrument inserted through the discharge opening 4, and to prevent this we provide a detached and relatively movable cover piece in the present form of a flat disk 18 which normally 5 rests upon and incloses the open side of the stopper, and the upper surface of which is preferably smooth and regular to prevent even it from being gripped easily. This cover piece, therefore, prevents access to the 10 stopper and if it were raised through some instrumentality, as, for instance a suction gripper inserted through the discharge opening 4, it would only serve to further close the latter and the stopper would be 15 left secure in its proper position.

When the bottle is inverted or tilted to a pronounced angular position, as shown in Fig. 2, the stopper valve 14, of course, gravitates from its normal position so that its 20 reduced portion 16 is opposite the seat 2 and because of the lesser diameter of this reduced portion a passage for the liquid is left as shown. The ribs 7 and 8 provide further passageways between them to the 25 mouth 4 by holding off the cap piece 18 from a close contact with the adjacent walls of the valve chamber, both top and sides. When the bottle is held with its neck in a substantially horizontal position, which is 30 the case during ordinary attempts to refill by submergence and similar ways, the valve member 14 will still move to its closed position in coöperation with the seat 2, as shown in full lines in Fig. 3, from the dotted line 35 position of Fig. 3 and the full line position of Fig. 2. This happens by reason of the fact that the rear or lower portion is heavier and the center of gravity is far to the left of the geometrical center. Thus, instead of 40 remaining in the open position of Fig. 2 with the enlarged portion 15 up against the cover piece 18, as shown in dotted lines in Fig. 3, only the then lower edge of the enlarged portion lies against the cap and with 45 the reduced portion 16 lying against and closing one side of the seat 2, the other edge or side of the enlarged portion rotates backward into operative engagement with the other side of the seat, as a result of a tilting 50 movement induced by the superior weight in the region of the reduced portion at the bottom or rear side of the stopper.

Of course, the last described function, to 55 be successful, depends largely upon the relative proportions of the parts, but the proportions shown, as will readily appear, give good results and may be generally followed. The stopper must emerge from the seat a sufficient distance to provide a suitable passage for the liquid, but at the same time it

must be checked from going so far that the fulcrum furnished by the contact of the reduced portion 16 with the seat, as shown in Fig. 3, will not be on the wrong side of the center of gravity, and in the present instance, the cap piece 18 constitutes an abutment for defining the extent of the unseating movement.

Attention is called to the fact that the practice of our present invention does not require unusual formations of the glass on the inside of the body portion 1 or neck proper of the bottle, as is required with most devices of the prior art, which formations are both expensive and impractical while the upper portion or cap piece 3 is small in size and simple in design rendering it easily molded or pressed into form and to be constructed from any one of a variety of materials. The parts are also easily assembled 5 after the bottle has been filled by adjusting 10 to their positions the stopper valve 14, the cap piece 18, the neck section 3, the stopper 5 and the seal strip 12, in the order named, and then spinning on or otherwise applying 15 the band 10.

We claim as our invention:

1. In a non-refillable bottle, the combination with a neck having a seat, of a stopper valve embodying an upper enlarged portion 20 normally occupying and sealing the seat and a lower reduced portion, the stopper being weighted at its lower end adapting it to tilt when the neck is held substantially horizontal and to rest with its reduced portion in contact with one side of the seat and, by such tilting, to bring the enlarged portion into operative relationship with the other side of the seat, the weighted portion being 25 smaller than both the seat and the interior of the neck, adapting it to be inserted from the mouth of the bottle, and an abutment spaced from and arranged above the seat to prevent the reduced portion of the stopper 30 from emerging too far from the latter to effect the tilting action described.

2. In a non-refillable bottle, the combination with a neck having a seat, of a stopper valve embodying an upper enlarged portion 35 normally occupying and sealing the seat and a lower reduced portion, the stopper being weighted at its lower end adapting it to tilt when the neck is held substantially horizontal and to rest with its reduced portion in contact with one side of the seat and, by such 40 tilting, to bring the enlarged portion into operative relationship with the other side of the seat and an abutment spaced from and arranged above the seat to prevent the reduced portion of the stopper from emerging too far from the latter to effect the tilting action described.

3. In a non-refillable bottle, the combination with a neck having a seat, of a stopper valve embodying a hollow open-ended upper 45

enlarged portion normally occupying and sealing the seat and a relatively heavier solid lower reduced portion adapting the stopper to tilt when the neck is held sub-
stantially horizontal and the stopper is resting with its reduced portion in contact with one side of the seat and, by such tilting, to bring the enlarged portion into operative relationship with the other side of the seat,
and a detached cover for the open top side of the hollow enlarged portion adapted to

contact with the stopper and arranged to itself obstruct the mouth of the bottle, said cover having a smooth and regular upper surface for the purpose described.
